241,010

COMBINED BOTTLE AND CARRYING HANDLE

Edwin L. Adair, 5985 S. Crocker St.,
Littleton, Colo. 80120

Filed Apr. 3, 1974, Ser. No. 457,495

Term of patent 14 years

Int. Cl. D9—01

U.S. Cl. D9—10

FIG. 1

FIG. 2

FIG. 4

FIG. 3

FIG. 5

FIG. 1 is a side elevational view of a combined bottle and carrying handle showing my new design;

FIG. 2 is a front elevational view;

FIG. 3 is a rear elevational view;

FIG. 4 is a top plan view; and

FIG. 5 is a bottom plan view thereof.

I claim:

The ornamental design for a combined bottle and carrying handle, as shown and described.
